(57) CLAIM

We claim the ornamental design for a bed, as shown and described.

DESCRIPTION

FIG. 1 is a perspective view of a bed according to the invention. The perspective view from the adjacent front corner being a mirror image thereto.

FIG. 2 is a front elevational view of a headboard of a bed according to the invention.

FIG. 3 is a top plan view of a headboard of a bed according to the invention.

FIG. 4 is a top plan view of a footboard of a bed according to the invention.

FIG. 5 is a front elevational view of a footboard of a bed according to an embodiment of the invention; and,

FIG. 6 is a side elevational view of a bed according to the invention. The view from the opposite side being a mirror image thereto.

The headboard and footboard are shown separately for clarity of disclosure.

The short, broken lines on the bed in the figures are for illustrative purposes only and form no part of the claimed invention. The backsides of the footboard and headboard are not shown and form no part of the claimed invention.
